Patented Dec. 24, 1957

181,776

COMBINED LAZY SUSAN, CANISTER SET AND COVER THEREFOR

Bennett Asquith, Roslyn Heights, N. Y.

Application December 8, 1955, Serial No. 39,239

Term of patent 14 years

(Cl. D44—6)

Fig. 1.

Fig. 2.

Fig. 3.

Fig. 4.

Fig. 1 is an elevational view of a combined lazy Susan, canister set and cover therefor, showing by new design;

Fig. 2 is an elevational view, with the canisters rotated 90° from the position of Fig. 1;

Fig. 3 is an elevational view with the canisters rotated 180° from the position of Fig. 1; and

Fig. 4 is an elevational view with the canisters rotated 270° from the position of Fig. 1.

The dominant features of my design reside in the portions shown by full lines in the drawings.

I claim:

The ornamental design for combined lazy Susan canister set and cover therefor, substantially as shown and described.
